Int. Reg. Date: **Nov. 11, 2015**

CLAIM

Int. Reg. Pub. Date: **Apr. 1, 2016**

The ornamental design for a leg-control mechanism for scooters, as shown and described.

(30) **Foreign Application Priority Data**

DESCRIPTION

May 12, 2015 (CN) 2015 3 0136805

The patent or application file contains at least one drawing executed in color. Copies of this patent or patent application publication with color drawing(s) will be provided by the Office upon request and payment of the necessary fee.

(51) LOC (10) Cl. **06-04**

1. Leg-control mechanism for scooters
